UNITED STATES PATENT OFFICE.

WILLIAM KNOWLES, OF ROCKVILLE, INDIANA, ASSIGNOR TO HIMSELF AND
GARRETT L. TEN BROOK, OF SAME PLACE.

KITCHEN-SAFE AND FLOUR-CHEST.

SPECIFICATION forming part of Letters Patent No. 325,416, dated September 1, 1885.

Application filed May 4, 1885. (No model.)

To all whom it may concern:

Be it known that I, WILLIAM KNOWLES, of Rockville, in the county of Parke and State of Indiana, have invented certain new and useful Improvements in Kitchen-Safes and Flour-Chests, of which the following is a full, clear, and exact description.

The object of my invention is to provide a new and improved kitchen-safe.

10 The invention consists in the peculiar construction and arrangement of parts, as herein-after fully described, and pointed out in the claims.

Reference is to be had to the accompanying drawings, forming part of this specification, in which similar letters of reference indicate corresponding parts in all the figures.

15 Figure 1 is a longitudinal sectional elevation of my improved kitchen-safe and flour-chest on the line $z z$, Fig. 3. Fig. 2 is a cross-sectional elevation of the same on the line $x x$, Fig. 1. Fig. 3 is a cross-sectional elevation of the same on the line $y y$, Fig. 1.

The kitchen-safe A has a wire-netting back, 20 A', near its bottom, and the doors A², having wire-netting panels, in its front, near the bottom.

25 Above the doors A² a door, B, extending from end to end of the safe, is hinged to the front of the same to swing downward, and behind the same grooved cleats C are secured to the inner surfaces of the sides of the case, and in the same rails D slide, which have pins E projecting from the outer sides, at or near the middles of said rails.

30 A dough-board, F, having an upwardly-projecting flange, F', at its inner or back edge, is arranged to slide on the rails D, and has downwardly-projecting pins G, which are behind the pins E, the rails D having 35 upwardly-projecting lugs D' at the inner ends, behind the inner edge of the kneading-board F.

40 A cup or trough, H, for containing soda, baking-powder, &c., is hung on the flange F' of the board F. Latches J are pivoted to cleats on the inner surfaces of the sides of the

safe, and have notches J' in their swinging ends.

Two flour-chests, K, are arranged above 50 the dough-board, and have inclined bottoms L, in the lower part of each of which a pocket, M, is formed, having a concave screen-bottom, N, in which a segmental brush or wiper, O, rests, which is secured to a lever, P, pivoted to the inner side of the front of the chest, and extends upward.

55 Each chest has a hinged lid. In the flat top of one chest a box, Q, for bread is held, and in the other chest a box, R, for seasoning materials—such as salt, &c.—is held. Behind the said boxes ventilating-screens S are secured in openings in the back of the chests.

60 A shelf, T, is arranged on the lower part of the safe.

By swinging the lever P the flour is sifted through the screen-bottoms N upon the kneading-board F, or a vessel placed thereon. When the said board is pulled out, its pins 70 G strike the pins E on the rails D and pull outward the said rails. When the board F is pulled out, the latches J automatically drop behind it and lock the said board in place. When the board F is to be pushed back, the 75 latches J are raised and the board pushed inward, and as the back edge of the board F strikes the lug D' the rails D are pushed inward.

80 I am aware that a meal-bin provided with a rotating reel and a flexible sieve below the same is old; and I am also aware that drawers have been held in horizontal positions when pulled out by means of sliding plates with which studs on the drawers engage; and I therefore do not claim such inventions.

85 Having thus described my invention, what I claim as new, and desire to secure by Letters Patent, is—

90 1. The combination, with a flour-chest having an inclined bottom, of a concave piece of wire-netting in the bottom, a segmental brush or wiper on the netting, and a pivoted

lever to which the wiper is secured, substantially as herein shown and described.

2. The combination, with the safe A, of the grooved cleats C, the sliding rails D, the board F, and the pins E and G, substantially as herein shown and described.

3. The combination, with the safe A, of the grooved cleats C, the sliding rails D,

having lugs D' on the rear ends, the sliding board F on the rails D, and of the pins E to and G, substantially as herein shown and described.

WILLIAM KNOWLES.
